FIG. 5.

FIG. 6.

ELECTRONIC FLASHER CIRCUITS

BACKGROUND OF THE INVENTION

The present invention relates to electronic timing circuits of simple construction and capable of controlling various load impedances such as lamps, buzzers, bells, relays and the like. Prior art devices include thermoresponsive bimetal switches and snap-action switches with an expansible pull wire. All of these devices controlled the opening and closing of at least one pair of contacts in the load current path. Such contacts are subject to wear and deterioration from corrosion, abrasion and electrical arcing, and thereby place inherent limitations on the useful life of the device of which they are a part. Also, when such devices are utilized as intermittent circuit breakers (flashers), the adjustability of rate and ratio is confined to relatively narrow ranges by inherent mechanical limitations. In addition, prior-art thermoresponsive switches of mechanical nature are apt to go out of adjustment upon mechanical impact, impact or due to variations in ambient temperature or changes in vane (buckling member) characteristics.

SUMMARY OF THE INVENTION

The present invention is embodied in and carried out by electronic timing circuits in which two complementary transistors are regeneratively interconnected with an RC network to enable either periodic or selective energization and de-energization of one or more load impedances. These circuits are capable of adjustment over wide ranges, are virtually shockproof, and exhibit a high degree of insensitivity to changes in ambient temperature. Due to the elimination of contacts, the useful life of these circuits is far greater than prior-art devices employing contacts.

BRIEF DESCRIPTION OF THE DRAWING

The present invention will be better understood when the written description thereof is read in connection with the accompanying drawing, of which:

FIG. 1 is a schematic wiring diagram of a first embodiment of the invention, showing the connections of its terminals to a source of power and a load;

FIG. 2 comprises a series of graphs representative of the voltages at various points in the circuit of FIG. 1 through a full cycle, said graphs being on a common time base;

FIG. 3 is a schematic wiring diagram of a second embodiment of the invention, showing the connections of its terminals to a source of power and two loads;

FIG. 4 is a schematic wiring diagram of a third embodiment of the invention, showing the connections of its terminals to a source of power and two loads;

FIG. 5 is a schematic wiring diagram of a fourth embodiment of the invention, showing the connections of its various terminals to a source of power and a load; and

FIG. 6 is a schematic wiring diagram of a fifth embodiment of the invention, showing the connections of its various terminals to a source of power and two loads.

DESCRIPTION OF THE PREFERRED EMBODIMENTS

Referring now specifically to the first embodiment shown in FIG. 1 and the related graphs shown in FIG. 2, when switch S is closed, the source of electromotive

force (EMF) consisting of battery B is connected to terminal T1 of the timing circuit. Thus, a small current begins to flow across the emitter-base junction of the normally non-conductive transistor Q1, and through resistances R1, R2 and R3 across the base-emitter junction of normally non-conductive transistor Q2 to ground. The collector-emitter junction of Q2 is made more conductive by this small turn-on current, thus enhancing turn-on current flow to Q1 across its emitter-base junction through R1 and the collector-emitter junction of Q2. Consequently, the emitter-collector junction Q1 is made more conductive, and current flows across that junction through C1, which acts as a very low impedance since it is initially uncharged, and through R3 and the base-emitter junction of Q2. This relatively large turn-on current causes Q2 to become fully conductive, thereby enabling maximum flow of turn-on current across the emitter-base junction of Q1 through R1 and the collector-emitter junction of Q2 to ground. Thus, Q1 is also rendered fully conductive, causing the collector voltage of Q1 to rise to a value a fraction of a volt less than the output voltage of battery B and thereby energizing load L1. Both Q1 and Q2 are rendered conductive virtually instantaneously with the closing of switch S due to the regenerative effect of the currents flowing through each transistor on the other. As shown in FIG. 2A, the voltage at the collector of Q1 rises sharply to a voltage nearly equal to that of battery B when switch S is closed at time T0. The voltage at the junction of C1-R2-R3 shown in FIG. 2B rises to substantially source voltage or higher at time T0 as a result of the collector of Q1 being a fraction of a volt below source voltage (C1 being effectively a short circuit when uncharged), to which is added the IR drop across resistance R3 and the base-emitter junction of Q2. With Q1 and Q2 now being conductive, C1 is charged by current flowing across the emitter-collector junction of Q1 and through R2 and the collector-emitter junction of Q2, paralleled by R3 in series with the base-emitter junction of Q2, to ground. As C1 becomes charged between times T0 and T1, it has an increasingly greater limiting effect on the base and collector current in Q2. When the current flowing across the collector-emitter junction of Q2 drops below the minimum required emitter-base current of Q1, the loading effect of L1 begins to cause the Q1 collector voltage to drop off a fraction of a volt from its initial maximum value as shown in FIG. 2B just prior to time T1. As the voltage at the junction of C1 and L1 decreases in this manner, the positive voltage at the C1-R2-R3 junction also decreases. When C1 has charged to a level at which the voltage at the C1-R2-R3 junction is too low to maintain Q2 conductive, the two transistors Q1 and Q2 are regeneratively cut off at time T1. As a result, the positive plate of C1 is suddenly switched to ground potential from a positive voltage nearly equal to that of the source. Thus, the voltage at the C1-R2-R3 junction becomes negative with respect to ground at time T1, as shown in FIG. 2B, since it is the negative plate of C1 which is connected to this junction and the positive plate is now grounded through the de-energized load L1. The negative voltage now appearing at the C1-R2-R3 junction is applied to the base of Q2 through R3, thereby holding Q2 non-conductive. At time T1, capacitance C1 begins to discharge through the loop formed by the collector-base junction of Q1 and resistances R1 and R2. This discharge continues to time T2, at which

time C_1 is completely discharged and the C_1 - R_2 - R_3 junction is at zero potential. Transistor Q_2 is no longer held off by a negative base voltage, and a new cycle is initiated at time T_2 . The circuit continues to repeat the cycle just described until switch S is opened.

It should be noted that the base transport factor beta (β) of each of the transistors Q_1 and Q_2 is a significant parameter in the performance of this circuit. The higher the beta factor, the better able a transistor is to handle the load current demand imposed by L_1 and the longer it will remain conductive. Where only a single load is controlled, the beta factor of the transistor to the collector of which the load is connected is of greater importance. Thus, the ON and OFF times of the circuit, i.e., the times when the load is energized and de-energized, respectively, are partially dependent upon the beta factors of transistors Q_1 and Q_2 and upon the magnitude of the load current. ON time is controlled principally by the values of C_1 and R_3 . The OFF time is controlled principally by the values of C_1 and R_1 plus R_2 . It should be noted that R_1 could be positioned between terminal T_1 and the emitter of transistor Q_1 , since its function is chiefly to limit current across the emitter-base junction of Q_1 and through the collector-emitter junction of Q_2 . With this modification, OFF time would be controlled by C_1 and R_2 . It is also possible to combine the resistances represented by R_1 and R_3 in a single emitter-follower resistance of Q_2 .

Referring now specifically to the embodiment shown in FIG. 3, the circuit shown there is a modified version of the embodiment shown in FIG. 1. The first capacitance C_1 has been removed, and a second capacitance C_2 has been inserted between the junction of R_1 and R_2 and the collector of Q_2 . Also, a second load L_2 has been connected between the emitter of Q_1 and the collector of Q_2 through terminals T_1 and T_4 . Both loads L_1 and L_2 are energized and de-energized in synchronization with one another, since Q_1 and Q_2 are saturated and cut off during the same time periods. This circuit operates in much the same manner as the first embodiment shown in FIG. 1, with a few differences. The voltage waveform at the collector of Q_2 in the second embodiment is like that at the collector of Q_1 in the first embodiment (see FIG. 2A). Also, the capacitance C_2 in the second embodiment is charged through the emitter-base junction of Q_1 and R_1 , and through the emitter-collector junction of Q_1 and R_2 . Capacitance C_2 is discharged through the loop formed by R_2 , R_3 and the base-collector junction of Q_2 . This circuit is subject to the same modification as the first embodiment.

Referring now specifically to the embodiment shown in FIG. 4, the circuit shown there is also a modified version of the embodiments shown in FIGS. 1 and 3. Two capacitances C_1 and C_2 are employed in the same position in the circuit which those capacitances had in FIGS. 1 and 3, respectively. This modification has been found to afford better control of the duty cycle and output pulse width. As in the second embodiment shown in FIG. 3, this circuit can control two loads L_1 and L_2 which are energized and de-energized in synchronization. As in the second embodiment shown in FIG. 3, either load may be eliminated. In operation, the capacitance C_1 is charged and discharged in the same manner as in the first embodiment shown in FIG. 1, and capaci-

tance C_2 is charged and discharged in the same manner as in the second embodiment shown in FIG. 3.

Referring now specifically to the embodiment shown in FIG. 5, this is a modification of the basic circuit shown in FIG. 1. This modified circuit is normally oscillatory when connected to a source of power (B_+), but can be turned off by connection of a predetermined impedance. As shown, resistance R_2 is broken up into two components, the first component R_{2a} being permanently connected from the emitter of transistor Q_1 through resistance R_3 to the base of transistor Q_2 . The second component R_{2b} is selectively connectable to a control terminal TC connected to the junction of R_{2a} , R_3 and C_1 . The turn-off component R_{2b} may be formed by a person touching the control terminal TC .

In operation, the circuit is normally oscillatory without keying resistance R_{2b} connected between the control terminal TC and ground. This circuit differs in operation from the preceding embodiments in that the initial turn-on current for Q_2 is drawn from the source of power (B_+) through the high resistance R_{2a} and R_3 across the base-emitter junction of Q_2 to ground. With Q_2 being thus rendered more conductive, turn-on current flows across the emitter-base junction of Q_1 through R_1 and across the collector-emitter junction of Q_2 to ground. Thus, current can now flow across the emitter-collector junction of transistor Q_1 and through capacitance C_1 , which acts as a virtual short circuit in its uncharged conduction, and through R_3 across the base-emitter junction of Q_2 to ground, thus augmenting the turn-on current of Q_2 . In this fashion, the two transistors Q_1 and Q_2 are regeneratively turned on almost instantaneously with the source of power B_+ to terminal T_1 . As C_1 accumulates an increasing amount of charge, it has a limiting effect on the emitter-collector current of Q_1 and on the base-emitter current of Q_2 . As with the previous embodiments, transistors Q_1 and Q_2 are regeneratively turned off when C_1 has become sufficiently charged. Discharge of C_1 then takes place through R_1 and R_2 and the base-collector junctions of Q_1 and Q_2 , and the cycle is continuously repeated.

Connection of resistance R_{2b} from the control terminal TC to ground has the effect of diverting the initial turn-on current from the base of Q_2 , and therefore inhibits the oscillation of the circuit. The circuit could be modified so that it is normally non-oscillatory by removing R_{2a} and making it selectively connectable between the source of power and the junction of C_1 and R_3 , omitting R_{2b} completely.

Referring now specifically to the embodiment shown in FIG. 6, this represents another modification of the basic circuits shown in FIGS. 1, 2 and 3. This modified circuit operates as a monostable multivibrator. By the application of either a positive-going pulse to control terminal TC_1 , or by application of a negative-going pulse to control terminal TC_2 , the loads L_1 and L_2 may be synchronously energized for a predetermined period of time. In the first instance, a positive pulse passing through coupling capacitance C_2 and resistance R_3 across the base-emitter junction of transistor Q_2 will render that transistor momentarily conductive. Thus, turn-on current for transistor Q_1 may flow across the emitter-base junction of Q_1 and through resistance R_1 and capacitance C_1 , which has its lower plate effectively connected to the source of power B_+ through

load L2 when Q2 is non-conductive. Consequently, Q1 becomes increasingly conductive and current flows across its emitter-collector junction and through R3 and the base-emitter junction of Q2 to ground, thus enhancing the conductivity of Q2. This increased conductivity results in increased current flow across the emitter-base junction of Q1 and through R1 and C1 across the collector-emitter junction of Q2. In this fashion, transistors Q1 and Q2 are regeneratively turned on virtually instantaneously upon the application of a control pulse at control terminal TC1. Optional resistance R1 acts to shunt current past capacitance C1 in order to lengthen the charging time of that capacitance, and thereby lengthen the on-time of transistors Q1 and Q2 and the period of energization of the loads L1 and L2. As capacitance C1 becomes increasingly charged with its lower plate connected to ground through the conductive transistor Q2, it will have an increasingly limiting effect on the current flowing across the emitter-base junction of Q1, thereby reducing the current flow across the emitter-collector junction of Q1 through R3 and across the base-emitter junction of Q2. When C1 is sufficiently charged, transistors Q1 and Q2 are regeneratively shut off, and the lower plate of capacitance C1 is again placed at source potential through load L2. Consequently, the upper plate of C1 goes to a voltage approximately double that of the source of power B+. The optional diode D1 connected between the source of power and the upper plate of capacitance C1 enables C1 to discharge virtually instantaneously through the power source. Thus, the recovery time of the circuit is minimized, so that it may readily handle closely-spaced input pulses.

The circuit will also operate in the foregoing manner if a negative input pulse is applied to control terminal TC2, thereby initiating current flow across the emitter-base junction of transistor Q1 and through R1 and C3 to the source of the pulse. This initial turn-on current for Q1 enables current flow across its emitter-collector junction through resistance R3 and across the base-emitter junction of Q2, thereby rendering that transistor more conductive. Consequently, current flow across the emitter-base junction of Q1 is enhanced by flow through C1 and across the collector-emitter junction of Q2. In this fashion, transistors Q1 and Q2 are regeneratively turned on virtually instantaneously upon the application of the input pulse. As before, the charging of C1 will eventually limit current flow and cause Q1 and Q2 to become regeneratively cut off. If the optional diode D1 were omitted, C1 could discharge across resistance R2. Alternatively, if optional resistance R2 were eliminated, C1 could discharge through diode D1.

There are numerous and varied uses for the several circuits disclosed herein. For example, the embodiments shown in FIGS. 1, 3 and 4 find ready application as flashers in automotive signal lamp circuits. In such applications, the battery B would correspond to the vehicle battery, the switch S would correspond to the turn signal switch or the emergency flasher switch, and the loads L1 and L2 would comprise light-emitting means such as incandescent lamps. The timing circuits enclosed by dotted lines in these figures can be constructed so compactly that they may be combined as a unit with a signalling device such as an incandescent lamp, in which the timing circuit may be enclosed by the lamp base or socket. The embodiment shown in

FIG. 5 is keyable by a resistance R2b which may be enclosed in an article of everyday wear, such as a ring, and the circuit could be employed to provide a pulsating input signal to control circuitry which would respond to said signal by opening a lock on an automobile car door, for example. The embodiment shown in FIG. 7 may be employed in any of the various applications for a monostable multivibrator, e.g., to standardize pulses of random widths.

The advantages of the present invention, as well as certain changes and modifications of the disclosed embodiments thereof, will be readily apparent to those skilled in the art. It is the applicant's intention to cover all those changes and modifications which could be made to the embodiments of the invention herein chosen for the purposes of the disclosure without departing from the spirit and scope of the invention.

What is claimed is:

1. An electronic flasher circuit comprising:
  1. a first transistor of a first conductivity type;
  2. a second transistor of a second conductivity type; and
  3. network means regeneratively interconnecting said first and said second transistors so that all transistor turn-on currents are confined to paths through said first and second transistors, said network means being operative, when a source of power and at least one load are connected to said timing circuit, to cause said transistors to alternate synchronously between the conductive and the non-conductive states and thereby alternately energize and de-energize said at least one load.
2. An electronic flasher circuit according to claim 1 wherein said network means comprises at least one resistance connected between the bases of said first and second transistors, a first terminal of said at least one resistance also being connected to the collector of said second transistor and the second terminal of said at least one resistance also being connected through a capacitance to the collector of said first transistor.
3. An electronic flasher circuit according to claim 1 wherein said network means comprises first, second and third resistances connected in series between the bases of said first and second transistors, the junction of said first and second resistances being connected to the collector of said second transistor and the junction of said second and third resistances being connected through a capacitance to the collector of said first transistor.
4. An electronic flasher circuit according to claim 3 and further comprising a load connected between the collector of said first transistor and the emitter of said second transistor.
5. An electronic flasher circuit according to claim 1 and further comprising a load connected between the collector of said first transistor and the emitter of said second transistor.
6. An electronic flasher circuit according to claim 1 wherein said network means comprises at least one resistance connected between the bases of said first and second transistors, the first terminal of said at least one resistance also being connected through a capacitance to the collector of said second transistor and the second terminal of said at least one resistance also being connected to the collector of said first transistor.
7. An electronic flasher circuit according to claim 1 wherein said network means comprises first, second

and third resistances connected in series between the bases of said first and second transistors, the junction of said first and second resistances being connected through a capacitance to the collector of the said second transistor and the junction of said second and third resistances being connected to the collector of said first transistor.

8. An electronic flasher circuit according to claim 6 and further comprising a first load connected between the collector of said first transistor and the emitter of said second transistor, and a second load connected between the collector of said second transistor and the emitter of said first transistor.

9. An electronic flasher circuit according to claim 1 and further comprising a first load connected between the collector of said first transistor and the emitter of said second transistor, and a second load connected between the collector of said second transistor and the emitter of said first transistor.

10. An electronic flasher circuit according to claim 1 wherein said network means comprises at least one resistance connected between the bases of said first and

second transistors, the first terminal of said at least one resistance also being connected through a second capacitance to the collector of said second transistor, and the second terminal of said at least one resistance also being connected through a first capacitance to the collector of said first transistor.

11. An electronic flasher circuit according to claim 1 wherein said network means comprises first, second and third resistances connected in series between the bases of said first and second transistors, the junction of said first and second resistances being connected through a second capacitance to the collector of said second transistor and the junction of said second and third resistances being connected through a first capacitance to the collector of said first transistor.

12. An electronic flasher circuit according to claim 11 and further comprising a first load connected between the collector of said first transistor and the emitter of said second transistor, and a second load connected between the collector of said second transistor and the emitter of said first transistor.
